P. E. GILBERT

HOSIERY

Filed Dec. 17, 1924

UNITED STATES PATENT OFFICE.

PHILIP E. GILBERT, OF CHICAGO, ILLINOIS.

HOSIERY.

Application filed December 17, 1924. Serial No. 756,408.

To all whom it may concern:

Be it known that I, PHILIP E. GILBERT, a citizen of the United States, and a resident of the city of Chicago, in the county of 5 Cook and State of Illinois, have invented certain new and useful Improvements in Hosiery; and I do hereby declare that the following is a full, clear, and exact description of the same, reference being had to the 10 accompanying drawings, and to the numerals of reference marked thereon, which form a part of this specification.

When a person wearing a stocking or sock walks, there is a natural tendency of the foot 15 to elongate and spread when weight is applied so that the stocking or sock on the foot is spread or stretched transversely, thereby causing the sock or stocking to be shortened longitudinally with the result 20 that the end of the stocking or sock is drawn against the ends of the toes thereby causing undue wear at the toe portion of the stocking or sock.

This invention relates to an improved 25 form of hosiery and more particularly to an improved toe portion for a sock or stocking, said toe portion being constructed preferably of a ribbed web material with all the wales thereof positioned transversely of the 30 foot portion of the sock or stocking, thereby permitting a longitudinal stretching at the toe portion to obviate wear particularly at the big toe section of the toe of the sock or stocking.

35 It is an object of this invention to provide an improved form of hose wherein a longitudinal stretching is permitted at the toe portion to materially obviate wear.

It is also an object of this invention to 40 provide a sock or stocking with the toe constructed of a material which will permit longitudinal stretching of the toe portion when the hose is on a person's foot so that the tendency of the toes to wear through the 45 toe portion of the hose is quite materially reduced.

Other and further important objects of 50 this invention will be apparent from the disclosures in the specification and the accompanying drawings.

This invention (in a preferred form) is 55 illustrated in the drawings and hereinafter more fully described.

On the drawings:

60 Figure 1 is a side elevation of an im-

proved hose provided with a toe portion embodying the principles of this invention.

Figure 2 is an enlarged side elevation of the foot portion of the improved hose.

Figure 3 is a top plan view of the foot 60 portion of the improved hose shown on a person's foot and illustrating in dotted lines the longitudinal stretching position of the toe portion of the hose when weight is applied to the foot.

Figure 4 is a fragmentary side elevation of the foot portion of a sock or stocking provided with a modified form of toe.

Figure 5 is a longitudinal section through the modified form of hose illustrated in 70 Figure 4.

As shown on the drawings:

The reference numeral 1 indicates the leg portion of a sock the upper end of which terminates in a ribbed top 2 while the lower 75 portion has integrally formed thereon a foot section 3. The hose has a heel portion 4 which may be of any selected construction desired.

The improved portion of the hose is the 80 toe portion 5 which is constructed of a ribbed web material having all the wales thereof positioned transversely of the foot portion 3 as clearly illustrated in Figures 2 and 3 of the drawings. The toe portion is 85 provided with side seams 6 as shown in Figure 2. The ribbed web material forming the toe 5 may form a continuous portion of the foot section 3 at the intersection 7 or the marginal edge of the toe 5 may be connected with the marginal edge of the foot section 3 by any other suitable method without forming a ridge or portion of excess thickness at the joining margins of the toe and foot sections.

It will thus be seen that an improved sock or stocking is provided having a ribbed web toe with all the wales positioned transversely of the foot portion instead of longitudinally in the accustomed manner. The transverse arrangement of the wales or ribbed web toe permits a longitudinal stretching of the toe portion from the full line position of Figure 3 to the dotted line position of said figure when an improved stock is being 105 worn and pressure is applied on the foot when the person is walking, producing an elongation of the foot so that the toes tend to move forwardly against the tip portion of the toe to stretch the same. With the 110

improved toe longitudinal stretching is of course permitted, thereby obviating undue wearing pressure on the tip portion of the toe so that tearing or wearing of holes in the toe is reduced, and discomfort or possible injury to the foot is obviated.

In the old type of toes in hose, the spreading action of the metatarsal portion of the foot causes a transverse stretching of the toe portion of the hose thereby tending to shorten the toe portion and stretch the same against the ends of the toes and toe nails so that holes are readily produced in the toe section due to the fact that the ordinary ¹⁰ sock or stocking is longitudinally nonelastic.

Figures 4 and 5 illustrate a modified form of toe for a sock or stocking and in this case the toe 8 is constructed of a thin sheet rubber or if desired a silk or cotton covered ²⁰ elastic webbing. The rubber toe portion 8 may be woven into the marginal end of the foot portion 9 of a hose or the margin of the rubber toe 8 may be cemented or vul-

canized in place to form a smooth junction between the toe and foot portion. The improved rubber toe 8 will permit lateral stretching when the hose is in use on a person's foot and the tendency to wear is thus greatly reduced affording a substantially ²⁵ hole-proof hose.

I am aware that many changes may be made and numerous details of construction may be varied through a wide range without departing from the principles of this invention, and I therefore do not purpose ³⁰ limiting the patent granted hereon, otherwise than necessitated by the prior art.

I claim as my invention:

A sock or stocking having a ribbed toe, each of the wales thereof extending in a ³⁵ plane transversely of the length of the foot to permit longitudinal stretching.

In testimony whereof I have hereunto subscribed my name.

PHILIP E. GILBERT.
